UNITED STATES PATENT OFFICE.

BENJAMIN F. KOCH AND SAMUEL BLOOM, OF BROOKLYN, NEW YORK.

DESIGN FOR A SHOE-LACE FASTENER.

SPECIFICATION forming part of Design No. 34,355, dated April 9, 1901.

Application filed February 26, 1901. Serial No. 49,008. Term of patent 14 years.

To all whom it may concern:

Be it known that we, BENJAMIN F. KOCH and SAMUEL BLOOM, citizens of the United States, and residents of the city of New York, borough of Brooklyn, in the county of Kings and State of New York, have invented and produced a new and original Design for a Shoe-Lace Fastener, of which the following is a full, clear, and exact description.

Reference is to be had to the accompanying drawings, forming a part of this specification, in which similar characters of reference indicate corresponding parts in all the figures.

Figure 1 is a perspective view of a shoe-lace fastener, showing our design. Fig. 2 is a front view, and Fig. 3 is a top view.

The leading feature of our design for a shoe-lace fastener consists in a cylindrical body portion having a hook-like projection at one side terminating in an enlargement, the front surface of the hook-like projection being on a transverse plane, with the end of the body

and the bend of the hook having an inclination toward the center of the body. 25

Referring particularly to the drawings, the body portion 1 is shown as cylindrical and has an annular flange at one end, and at one side of the body is a curved or hook-like projection 2, terminating in a ball-like enlargement 3, and the bend of the hook-like projection has an incline toward the center of the body. 30

Having thus described our invention, we claim as new and desire to secure by Letters Patent—

The design for a shoe-lace fastener, as herein shown and described.

In testimony whereof we have signed our names to this specification in the presence of two subscribing witnesses. 40

BENJAMIN F. KOCH.

SAMUEL BLOOM.
